US0D1070221S

(12) **United States Design Patent** (10) **Patent No.:** **US D1,070,221 S**
(45) **Date of Patent:** **** Apr. 8, 2025**

(54) **LIFT**

(71) Applicant: **Oshkosh Corporation**, Oshkosh, WI (US)

(72) Inventors: **Neil Doherty**, Oshkosh, WI (US); **Morten Ellis**, Oshkosh, WI (US); **Joe Butler**, Oshkosh, WI (US); **Benedict Calland**, Oshkosh, WI (US)

(73) Assignee: **OSHKOSH CORPORATION**, Oshkosh, WI (US)

(**) Term: **15 Years**

(21) Appl. No.: **29/898,029**

(22) Filed: **Jul. 21, 2023**

(51) **LOC (15) Cl. 12-05**

(52) **U.S. Cl.**

USPC **D34/28; D34/34**

(58) **Field of Classification Search**

USPC D34/28, 34, 35

CPC B66F 11/04; B66F 13/00; B66F 17/006

See application file for complete search history.

(57) **CLAIM**

The ornamental design for a lift as shown and described.

DESCRIPTION

FIG. 1 is a front, left perspective view of the claimed design; FIG. 2 is a front view of FIG. 1; FIG. 3 is a rear view of FIG. 1; FIG. 4 is a right side view of FIG. 1; FIG. 5 is a left side view of FIG. 1; FIG. 6 is a top view of FIG. 1; FIG. 7 is a bottom view of FIG. 1; and, FIG. 8 is a rear, right perspective view of FIG. 1. Broken lines formed by equal or substantially equal length dashes show unclaimed portions of the design and form no part of the claimed design. Broken lines formed of unequal length dashes (i.e., dash-dot-dash) show boundaries between claimed and unclaimed portions of the design.

1 Claim, 8 Drawing Sheets
